QUICK PRIMING AND IGNITION ATTACHMENT FOR OIL BURNERS

August Giarnese, Torrington, Conn.

Application November 7, 1933, Serial No. 696,933

8 Claims. (Cl. 158—81)

This invention relates to oil burners, and more particularly to a quick starting or "priming" device for attachment to the feed line of an oil range burner.

One object of this invention is to provide a manually operated pressure bulb device for quickly causing oil to flow from the feed line into the wick of the oil burner.

A further object is to provide means for electrically igniting the oil in the burner wicks by an interrupted spark circuit which is set into operation at the same time the wick is primed.

A further object is to provide a device of the above nature which will be simple in construction, inexpensive to manufacture, easy to install and manipulate, compact, ornamental in appearance, and very efficient and durable in use.

With these and other objects in view there has been illustrated on the accompanying drawing, one form in which the invention may be conveniently embodied in practice.

In the drawing:

Fig. 1 is a side elevation, mostly in section, of a complete burner unit and fuel supply system, the electrical circuit being shown diagrammatically.

Fig. 2 is an enlarged vertical sectional view through the combined pressure bulb and electrical switch unit in inoperative position.

Fig. 3 is a view similar to Fig. 2 showing the bulb and switch in operative positions.

In the ignition of the wicks of conventional forms of oil burners, it is generally necessary to wait a considerable period of time after opening the oil feed valve before the actual ignition can be accomplished owing to the slow speed at which the oil flows into the wick. By means of the present invention, the "priming" of the wick is expedited, and means are provided for the electric ignition thereof without requiring the use of matches. The burner will also be prevented from overflowing, and thereby smoking and carbonization is prevented.

Referring now to the drawing in which like reference numerals denote corresponding parts throughout the several views, the numeral 10 indicates an oil supply tank supported in an inverted position above a reservoir bowl 11 by means of a bracket 12. The tank 10 has a restricted neck provided with the usual form of valve cap 13 which permits the fuel oil to escape from the tank into the bowl 11 and maintain a constant predetermined level of fuel therein.

The fuel oil flows from the reservoir 11 to a burner unit 14 (or a plurality of such units if desired) by means of a feed line pipe 15. The burner unit 14 comprises the usual central annular burner chamber surrounding which are a plurality of wick channels 17 and 17a, containing wicks 18 and 18a, respectively. Extending

upwardly from the channels 17, 17a embracing said wicks 18 and 18a are two pairs of concentric perforated air supply cylinders 19 which are supported by four upright annular ribs 20 formed integral with the burner bowl. When in use, the flow of fuel from the reservoir 11 may be regulated by means of a manual control valve 21 located at an intermediate position in the feed pipe 15.

In order to permit the wicks to be rapidly primed and then immediately ignited, provision is made of a rubber pressure bulb 22 located at the upper end of a vertical pipe 23 attached to the feed pipe 15 by means of a T fitting 24, the latter being located preferably at an intermediate position on the feed pipe 15 between the valve 21 and the reservoir 11. The manual squeezing of the bulb 22 will force the oil in the pipe 15 at the right of the T fitting 24 to flow up into the burner bowl 16 in sufficient quantity to instantly "prime" the wicks and start the operation of the burner. A check valve 25 will preferably be located in the fuel pipe 15 at the left of the T fitting 24 to prevent back flow of oil from the right-hand portion of the pipe 15.

It will be understood, however, that it is within the scope of the present invention to combine the check valve 25 and the T fitting 24 into a single unit if desired. The bulb 22 is made "obovate" in shape, having a thin flexible side 30 wall of resilient rubber 26 which, when manually contracted, will automatically expand to its original shape. A vent valve 27 of the usual construction is located in the apex of the bulb 22, said valve 27 serving to prevent air from escaping through the top of the bulb when it is compressed, but allowing free flow of air into the bulb when the bulb is released. The lower narrow neck end of the bulb 22 is constructed from substantially heavy rubber forming an apertured collar 28 integral with the lower wall 26 thereof. In use, the collar 28 of the bulb will be slipped over the upper end of the pipe 23 with a tight fit thereupon.

In order to cause the oil in the wick to immediately ignite as soon as the priming operation has occurred, provision is made of a pair of spark plugs 29 and 30 attached to the burner bowl 16 and forming a pair of spark gaps with the ribs 20 across the wick channels 17, 17a (see Fig. 1). The plugs 29 and 30 are connected with a suitable spark coil 31 by means of a pair of conductors 33 and 33a, the conductor 33a being grounded to the burner bowl 16, as by a screw 37. The sparking circuit is controlled by a special switch mechanism 34 inclosed within the priming bulb 22, and connected with the spark coil 31 and a battery 32 or other suitable source of electricity by means of a pair of conductors 35 and 36.

The switch mechanism 34 comprises a pair of

thin flat metal movable contacts 38 and 39 constructed of resilient material in the form of opposed semi-loops 40 and 41. The exterior portion of the loops conforms substantially to the contour 5 of the wall of the bulb 26, while the inner ends of said loops are turned downwardly and are offset inwardly to form a pair of parallel contact terminals 42 and 43, which are adapted to electrically engage each other when the bulb is compressed to complete the sparking circuit (see Fig. 10 3). The contacts 38 and 39 are directed downwardly out of the bulb 22 through suitable slits 15 44 and 45 provided in the collar 28, and are bent back upon themselves around portions of said collar 28 to provide a firm anchorage thereon. The exterior anchored portions of said contacts 15 38 and 39 may be provided with terminal eyes 46 and 47, to which the conductors 35 and 36 may be detachably or permanently connected.

20 One advantage of the use of the flexible loop form of switch contacts in the bulb 22 is that the resiliency of the loops 40 and 41 will assist in expanding the bulb to its original shape (Fig. 2) after said bulb has been compressed to the position shown in Fig. 3.

Operation

In the operation of lighting the burner 14, it will first be necessary to open the manual control valve 21, and then by merely squeezing the bulb 22, the burner bowl will be primed with sufficient oil to rapidly saturate the wicks 18 and 18a. The oil vapor arising from said wicks will then be immediately ignited by the sparks passing across the wick channels 17 and 17a.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a heating apparatus, a liquid fuel reservoir, a burner, means for conducting fuel from said reservoir to said burner, a check valve in said fuel conducting means, means having a connection with said pipe between said check valve and said burner for manually forcing air quickly into said fuel conducting means to force fuel rapidly into said burner to prime said burner more rapidly than would occur by the natural flow of said fuel.

2. In a heating apparatus, a liquid fuel reservoir, a wick-type fuel burner, a pipe for conducting fuel from said reservoir to said burner, a check valve in said pipe to prevent back flow of fuel, and manually operated means having a connection with said pipe between said check valve and said burner for forcing a portion of the liquid fuel from said connection and said burner into said burner to quickly saturate the wick thereof.

3. In a heating apparatus, a liquid fuel reservoir, a wick-type fuel burner, a pipe for conducting fuel from said reservoir to said burner, a check valve in said pipe to prevent back flow of fuel, and a manually operated flexible air bulb having a connection with said pipe between said check valve and said burner for forcing the liquid fuel between said check valve and said burner

into said burner to quickly saturate the wick thereof.

4. In a heating apparatus, a liquid fuel reservoir, a wick-type fuel burner, a pipe for conducting fuel from said reservoir to said burner, a check valve in said pipe to prevent back flow of fuel, a vertical pipe having a connection with said fuel conducting pipe between said check valve and said burner, and an air injecting device attached to the upper end of said vertical pipe for forcing the liquid fuel from said conducting pipe into said burner to quickly prime the wick.

5. In a heating apparatus, a liquid fuel reservoir, a fuel burner, a pipe for conducting fuel from said reservoir to said burner, said burner including electrical starting means connected with a source of electricity, means having a connection with said conducting pipe for simultaneously closing the circuit through said electrical starting means and introducing a portion of the liquid from said conducting pipe into said burner for priming the same, and a check valve between said reservoir and said connection to prevent reverse flow of said liquid fuel in said pipe.

6. In a heating apparatus, a liquid fuel reservoir, a fuel burner, a pipe for conducting fuel from said reservoir to said burner, electrical means for igniting the fuel vapor in said burner, a manually-operated rubber pressure bulb having a connection with said pipe for forcing liquid from said pipe up into said burner for priming it, a check valve between said reservoir and said connection, said rubber bulb having an interior switch mechanism adapted to be closed by the contraction of said bulb for making the circuit through said electrical ignition means, the contacts of said switch mechanism being adapted to be opened automatically by the expansion of said bulb when the pressure thereon has been released.

7. In a heating apparatus, a liquid fuel reservoir, a fuel burner, a pipe for conducting fuel from said reservoir to said burner, electrical means for igniting the fuel vapor in said burner, a manually-operated rubber pressure bulb having a connection with said pipe for forcing liquid from said pipe up into said burner for priming it, a check valve in said pipe between said reservoir and said connection, said rubber bulb having an interior switch mechanism adapted to be closed by the contraction of said bulb for making the circuit through said electrical ignition means, the contacts of said switch mechanism being adapted to be opened automatically by the expansion of said bulb when the pressure thereon has been released, said contacts being resilient and U-shaped.

8. In a heating apparatus, a liquid fuel reservoir, a fuel burner, a pipe for conducting fuel from said reservoir to said burner, electrical means for igniting the fuel vapor in said burner, a manually-operated rubber pressure bulb having a connection with said pipe for forcing liquid from said pipe up into said burner for priming it, a check valve in said pipe between said reservoir and said connection, said rubber bulb having an interior switch mechanism adapted to be closed by the contraction of said bulb for making the circuit through said electrical ignition means, the contacts of said switch mechanism being adapted to be opened automatically by the expansion of said bulb when the pressure thereon has been released, said contacts being resilient and U-shaped and having their extremities inwardly offset into parallel relation.
